UNITED STATES PATENT OFFICE.

WILLIAM H. PUTNAM, OF LITCHFIELD, ILLINOIS.

BROOM-CLAMP.

SPECIFICATION forming part of Letters Patent No. 373,785, dated November 22, 1887.

Application filed May 13, 1887. Serial No. 238,048. (No model.)

To all whom it may concern:

Be it known that I, WILLIAM H. PUTNAM, of Litchfield, in the county of Montgomery and State of Illinois, have invented certain new and useful Improvements in Broom-Clamps; and I do hereby declare the following to be a full, clear, and exact description of the invention, such as will enable others skilled in the art to which it pertains to make and use it, reference being had to the accompanying drawings, which form part of this specification.

My invention relates to an improvement in broom-clamps; and it consists in a clamp which is formed of two **U**-shaped independent parts which have their ends turned inward toward each other, with a tie which secures rigidly together the overlapping ends of the two parts of the clamp upon opposite sides of the broom, as will be more fully described and claimed hereinafter.

The object of my invention is to provide a clamp for brooms which is made in two separate and independent pieces, which are applied over opposite edges of the broom and then clamped together by a wire which is passed through the broom at right angles to the clamps.

Figure 1 represents a side elevation of a broom-head to which my invention is applied. Fig. 2 is a perspective of the clamp detached from the broom.

A represents an ordinary broom-head, and B the two parts of the clamp, by means of which the straws are fastened together. Each one of these parts of the clamp consists of a **U**-shaped piece of wire long enough to extend from one edge past the center of the broom, and which has its two ends, C, turned inwardly toward each other, as shown. Each clamp

catches over one side of the head of the broom, 40 and the inwardly-turned ends C are forced inwardly toward each other into the straw, not only for the purpose of keeping the ends out of the way, but for the purpose of clamping or holding the straws tightly together. The inner ends of the two parts of the clamp overlap each other upon each side of the head, and these overlapping ends are secured rigidly together by means of the metallic tie D, which extends horizontally through the straw and 45 catches over the overlapping ends upon each side of the head.

The four inwardly-turned points of the two parts of the clamp being made to catch in the straws and the tie being made to extend through 55 the head, the clamp is held rigidly in position under all circumstances, and the straws of the broom are made stiffer and stronger thereby.

This clamp can be applied at any desired point upon the broom-head, according to the 60 stiffness it is desired to give to the straw.

Having thus described my invention, I claim—

A clamp for a broom, composed of the two parts B, which are passed over opposite edges 65 of the broom-head, and which are provided with inwardly-extending hooks or bends C at their inner ends, which engage the broom-straw, in combination with the wire D, which is passed through the broom at right angles to 70 the clamps for the purpose of securing them together, substantially as shown.

In testimony whereof I affix my signature in presence of two witnesses.

WILLIAM H. PUTNAM.
